CLAIM

The ornamental design for a wall mount hand mirror, as shown and described.

DESCRIPTION

FIG. 1 is a front perspective view of a wall mount hand mirror according to the present invention, showing the wall mount hand mirror in a partially extended configuration. FIG. 2 is a fragmentary perspective view thereof, on an enlarged scale.

FIG. 3 is a front elevation view thereof, showing the wall mount hand mirror in a fully extended configuration.

FIG. 4 is a rear elevation view thereof.

FIG. 5 is a top plan view thereof.

FIG. 6 is a bottom plan view thereof.

FIG. 7 is a right side elevation view thereof.

FIG. 8 is a left side elevation view thereof.

FIG. 9 is a front elevation view thereof, showing a hand mirror part of the wall mount hand mirror pivoted to a horizontal orientation.

FIG. 10 is a fragmentary right side elevation view thereof, on an enlarged scale.

FIG. 11 is a right side elevation view thereof.

FIG. 12 is a front elevation view of the wall mount hand mirror of FIG. 1, showing the wall mount hand mirror in a retracted configuration, and the hand mirror part of the wall mount hand mirror in a vertically extended position.

FIG. 13 is a front elevation view thereof, with the hand mirror removed; and,

FIG. 14 is a fragmentary top plan view thereof, on an enlarged scale.

The portions of the wall mount hand mirror shown in broken lines form no part of the claimed design. The broken line showing a portion of a wall surface in FIG. 1 and of the reflection in the mirror of FIGS. 1, 3, and 4 illustrates the environment of the claimed design and forms no part thereof.
